[57] CLAIM

The ornamental design for a support stand for use in repairing saddles, as shown and described.

DESCRIPTION

FIG. 1 is a perspective view of a support stand for use in repairing saddles showing my new design;
FIG. 2 is a side elevational view; and

FIG. 3 is an end elevational view thereof.

The side and end of the support stand not shown are substantially the same in appearance as the side and end shown in FIGS. 2 and 3 respectively.

FIG. 1

FIG. 2

FIG. 3
